O. POULSEN

CENTRIFUGAL PUMP

Original Filed May 10, 1920

Inventor.

Oscar Poulsen,

By A.S. Paré
attorney.

UNITED STATES PATENT OFFICE.

OSCAR POULSEN, OF ALAMEDA, CALIFORNIA.

CENTRIFUGAL PUMP.

Application filed May 10, 1920, Serial No. 380,256. Renewed March 5, 1927.

This invention relates to centrifugal pumps and more especially to means for balancing the impeller therein, and keeping it centered in its casing.

5 The invention may be best understood from an inspection of the accompanying drawing, and the description thereof, which follows.

In the accompanying one sheet of drawing 10 I have illustrated the invention in its simplest form.

The figure shows a side elevation of a pump, the main body thereof being sectioned to show the interior.

15 The pump is provided with a base 1 having bearings 2, 3, and mounted on a suitable foundation, not shown, to which it may be secured by bolts, as 4, 5 is the pump shaft, adapted to rotate in the bearings 2, 3, and 20 having a drive pulley 6 thereon. The bearing at 3 is provided with a bushing 7, a gland 8 and packing 9. To a flange, or ears, 10 at the end of the bearing 3, is bolted the pump casing, 11, consisting of two central 25 sections substantially alike and bolted together and which has a discharge at 12, and a suction at 13. To the discharge and suction, pipes 14 may be applied, leading to and from any desired points. To the end of shaft 30 5 is applied the impeller, rotated thereby, having the usual impelling channels 15, and the hub portions 16 and 17. The hub member 16 has the central suction opening 18, registering with the suction 13, and communicating with the impelling channels 15. The hub member 17 is provided with a series 35 of channels 19, extending axially through it. It will be observed that the width, from end to end of the hubs, is less than the width 40 of the casing, thus leaving narrow channels 20 and 21, which communicate with the chambers 22 and 23, respectively, at the sides of the impeller. These channels are widened and narrowed by the lateral vibration of the 45 impeller.

The operation may be thus described. When the impeller shifts to the right, channel 20 is widened, and suction takes effect from chamber 22, and the pressure on that 50 side of the impeller is reduced. At the same time channel 21 is narrowed, and thereby suction from chamber 23 is reduced, and pressure on that side of the impeller is increased. The impeller, under the influence 55 of these forces tends to the left. If the impeller moves laterally too far to the left, the

reverse action of that, just described, takes effect. The impeller is by this means balanced and centered in its casing.

Having thus described my invention, and 60 an embodiment of it, in the full, clear and exact terms required by law, and knowing that it comprises novel, useful and valuable improvements in the art to which it pertains, I here state that I do not wish to be limited 65 to the precise construction and arrangement of the several parts, as herein set forth, as the same may be variously modified by a skilled mechanic without departing from the 70 spirit of the invention.

What I claim and desire to secure by Letters Patent of the United States, is the following, to wit:—

1. A centrifugal pump comprising in combination a casing, consisting of two sections substantially alike and secured together, and having central annular portions, a suction pipe provided with a flange secured to the annular portion of one of said sections and a bearing on the side opposite said suction pipe secured to the annular portion of the other of said sections, an impeller centrally located within said sections, said impeller being spaced from the casing sections to provide a variable pressure 75 chamber on each side of said impeller, said impeller having a uniform shaped hub on each side thereof, and having their opposite extremities positioned internal to said annular portions with a light clearance therebetween, one of said hubs abutting said flange on said suction pipe and the other having longitudinal channels therebetween abutting the bearing, the width between the hubs being less than the width between the suction 80 pipe flange and bearing, said flange, hubs and bearing, co-operating with said annular portions to form a chamber on each side of said hubs of substantially the same diameter, surrounding the entire diameter of said hubs 85 and adapted to connect directly at one time 90 one of said variable pressure chambers with the suction pipe.

2. A centrifugal pump comprising, in combination, a casing, consisting of two centrally disposed sections, a suction pipe provided with an annular flange secured to said casing on one side thereof and on the opposite side a bearing having an annular flange secured to said casing, an impeller mounted 105 centrally in said casing to provide a variable pressure chamber on each side of said im-

eller, a hub on each side of said impeller, one of said hubs having a central suction opening abutting said suction pipe and the other provided with a series of axial channels abutting said bearing and the spaces between said suction pipe and said suction opening and between said axial channels and said bearing being provided with

passages, each one of said passages adapted to connect at one time said pressure chamber 10 directly with the suction pipe.

In testimony that I claim the foregoing I have hereto set my hand this 3 day of May, 1920.

OSCAR POULSEN.
